UNITED STATES PATENT OFFICE.

LOREN C. COX, OF QUINCY, ILLINOIS.

ELECTRIC CLOCK.

No. 808,016.

Specification of Letters Patent.

Patented Dec. 19, 1905.

Application filed July 6, 1905. Serial No. 268,458.

To all whom it may concern:

Be it known that I, LOREN C. Cox, a citizen of the United States, residing at Quincy, in the county of Adams and State of Illinois, have 5 invented a new and useful Electric Clock, of which the following is a specification.

This invention relates to electrically-wound clocks, and has for its principal object to provide a novel form of clock of that class in 10 which an actuating-weight is elevated to operative position at predetermined intervals.

A further object of the invention is to provide a clock in which a pair of actuating-weights are so arranged as to exercise a practically uniform propelling force at all times 15 and to so arrange the parts that said weights are alternately elevated.

A still further object of the invention is to provide a device of this class in which the propelling-weight is raised by means of an electromagnet in such manner that the weight will 20 be thrown beyond the point at which the electromagnetically-actuated means stops.

A still further object of the invention is to 25 provide a novel form of automatic circuit-closer and circuit-closer-resetting mechanism under the control of the weight or weights.

A still further object of the invention is to provide a device of this class in which springs 30 or like members for holding the armature of the electromagnet in place are dispensed with, the armature moving by gravity away from the electromagnet as soon as the latter is de-energized.

35 With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure 40 may be made without departing from the spirit or sacrificing any of the advantages of the invention.

In the accompanying drawings, Figure 1 is 50 a sectional elevation of an electrically-wound clock constructed in accordance with the invention. Fig. 2 is a side elevation of the same, partly in section. Fig. 3 is a detail perspective view of the clock-actuating weights, illustrating the armature and its connections. Fig. 4 is a detail perspective view of the circuit-closer detached. Fig. 5 is a similar view of 55 the pawl for holding the circuit-closer with

the circuit broken. Fig. 6 is a detail perspective view of the arm-carrying sleeve receiving motion from the armature and transmitting motion to the weighted levers. 60

Similar numerals of reference are employed to indicate corresponding parts throughout the several figures of the drawings.

The working parts of the clock are supported by a suitable frame 10, which may be 65 arranged within a casing of any desired character. (Not shown.) The clock-train 11 is of any suitable character and includes a main shaft or arbor 12, an escapement mechanism 13, and a pendulum 14. The shaft or arbor 70 12 carries a minute-hand 15 and also forms a support for the hour-hand 16, the latter being connected to the main arbor by back-gearing in the usual manner.

Rigidly secured to the main arbor 12 are 75 two ratchet-disks 17 and 18, each of which is provided with any desired number of teeth, and the teeth of the two disks are arranged in alignment with each other. Mounted loosely on the arbor are the hubs of a pair of 80 levers 19 and 20, each of which is provided at its outer end with a weight 21, and on each lever is a pawl 22, that is held in engagement with the teeth of one of the ratchet-disks, and said weighted levers serve as a propelling 85 means for the clock-train. From the hub of each lever projects an arm 23, that is arranged at a point diametrically opposite the lever and controls the operation of the circuit-closing device. 90

At a point between the hubs of the two weighted levers the shaft is provided with a hub 24, having a pair of projecting arms 25 and 26, and from the lower end of the latter arm project two pins 27 and 28, that are 95 adapted to engage, respectively, with the lower edges of the levers 19 and 20 and move said levers from the lowest to the highest position, this operation occurring at regular intervals of eight or ten minutes in the present 100 construction; but the time may be altered if the gearing is differently proportioned.

To the lower portion of the frame is pivoted an armature 30 in the form of a soft-iron plate that is arranged immediately below the 105 poles of a pair of electromagnets 31 and normally moves to the lowest position by gravity when the electromagnets are de-energized. The pole-pieces are preferably capped with brass or other diamagnetic material in 110 order to prevent the armature clinging thereto from the effects of residual magnetism.

- From the armature extends an arm 33, that is connected by a rod 34 to the arm 25, and each time the armature is attracted rod 34 is pulled down sharply and one or other of the 5 pins 27 28 engages against the weighted lever which it is to actuate and throws said lever from the dotted-line position (shown in Fig. 1) to the uppermost of the full-line positions shown in said figures, the mechanical lift of 10 the pins being approximately from the dotted-line position to the horizontal and the further movement of the lever being under the impetus imparted by the sudden operation of the armature.
- 15 Pivoted to the frame or to a suitable bracket carried thereby is a circuit-closer 36 of the character more clearly shown in Fig. 4. The upper curved edge of the circuit-closer is eccentric to its pivot-point, and when the 20 circuit-closer is moved by its spring 37 this curved surface slidably engages a spring-contact 38, that forms one terminal of a circuit which includes an electromagnet and a suitable source of energy, thereby energizing the 25 electromagnet. The sliding friction between the two contacts will keep them bright and prevent corrosion. The circuit-closer 36 is provided with an upwardly-projecting tooth 38', that is normally engaged by a pawl 39, 30 pivoted at 40 to the frame, and said pawl carries a pair of projecting lugs 41, that are disposed immediately above the arms 23, so that each time one of the arms assumes the dotted-line position (shown in Fig. 1) it will raise 35 the pawl to the dotted-line position shown in said figure, and the circuit-closer will be released and will move under the influence of its spring 37 into engagement with the contact 38, thereby completing the circuit and 40 causing the armature and its connected mechanism to move said weighted lever to the elevated position.
- The lower portion of the circuit-closer 36 is bifurcated, forming a pair of arms 40, that 45 straddle the connecting-rod 34, and said arms are disposed in the path of movement of the two arms 23, carried by the weighted levers. These arms 40 are engaged by the arms 23 as 50 the weighted levers are moved to the elevated position and move the circuit-closer from circuit-closing position to circuit-breaking position, being the position shown in full lines in Fig. 1.
- At the upper portion of the frame is arranged 55 a pivoted buffer-block 45, preferably having a covering 46, of rubber or other elastic material, which will receive the impact of the weighted levers and check the movement of the same without unnecessary noise.
- 60 In the operation, the parts being in the position shown in Fig. 1, both weights are operative. As they gradually descend the weighted lever 20 will reach the dotted-line position shown in Fig. 1, while the weighted 65 lever 19 approaches the horizontal. As soon as the arm 23 of lever 20 engages the pawl 39 and raises the same from the tooth 38 the circuit-closer 36 will be moved by spring 37 into engagement with the contact 38', completing the circuit of the electromagnet. The armature 30 is instantly attracted, and the arm 25 is pulled down, while arm 26 is thrown upward, and the pin 28 will engage under the weighted lever 20 and will throw the same to the highest position, its pawl 22 automatically 70 engaging with a tooth of the ratchet-disk. The movement of the lever 26 ceases before pin 27 comes in contact with the weighted lever 19, the continued movement of the lever 20 being under the impetus imparted by the sudden movement of the armature.
- With a device constructed in accordance with this invention the propelling-weight is practically uniform at all times, and movement of each lever from its lowest to its highest position takes place when the weight of the other lever is at the greatest horizontal distance from the main arbor, and therefore in the most effective position.
- Having thus described the invention, what 90 is claimed is—
1. In a clock of the class described, a shaft or arbor, a pair of ratchet-wheels rigidly secured thereto, weighted levers pivotally mounted on said arbor, pawls carried by the levers and engaging the ratchet-wheels, a loose sleeve carried by the shaft and provided with a pair of projecting arms, pins carried by one of said arms and arranged to engage the lever, an electromagnet, the armature of which is operatively connected to the opposite arm, and an energizing-circuit for said magnet, including the contacts under the control of said levers.
  2. In a clock of the class described, a shaft 105 or arbor, a pair of ratchet-wheels rigidly secured thereto, weighted levers pivotally mounted on said shaft, pawls carried by the levers and engaging the ratchet-wheels, a loose sleeve carried by the shaft and provided with 110 a pair of projecting arms, pins carried by one of said arms and arranged to engage the levers, an electromagnet having an armature connected to the opposite arm, a magnet-circuit including a stationary and a movable contact, 115 and a retaining device for holding the movable contact in circuit-breaking position, said retaining device being under the control of the levers.
  3. In a clock of the class described, a shaft 120 or arbor, a pair of ratchet-wheels rigidly secured thereto, a pair of weighted levers mounted loosely on the shaft and provided with projecting arms, pawls carried by said levers and arranged to engage the ratchet-wheels, an 125 electromagnet having an armature, means for transmitting movement from the armature to the levers to alternately elevate the same, a magnet-circuit including a fixed terminal and a pivotally-mounted block forming the second 130

terminal, a pawl for engaging the block and holding the same in circuit-breaking position, said pawl being disposed in the path of movement of the lever-carried arms to permit release 5 of the block when the weighted ends of the levers are depressed, the lower portion of the block being disposed in the path of movement of said arms, whereby the block may be restored to circuit-breaking position when the 10 levers are elevated.

4. In a clock of the class described, the combination with a shaft or arbor, a pair of ratchet-wheels rigidly secured thereto, a pair of weighted levers pivotally mounted on the arbor 15 and provided with projecting arms, pawls carried by said levers and engaging the ratchet-wheels, a sleeve loosely mounted on the arbor and provided with a pair of projecting arms, lever-engaging pins carried by one of said 20 arms, an electromagnet, a pivoted armature

arranged within the field of force of the electromagnet, and connected to the second arm, a fixed contact, a pivotally-mounted contact, a spring tending to force said pivotally-mounted contact toward the fixed contact, a pawl engaging 25 said pivotally-mounted contact and normally holding the circuit open, said pawl being disposed in the path of movement of the lever-carried arms, and spaced arms carried by the pivotally-mounted contact and also arranged in the path of movement of said lever-carried arms.

In testimony that I claim the foregoing as my own I have hereto affixed my signature in the presence of two witnesses.

LOREN C. COX.
